[57] CLAIM

The ornamental design for a pair of support brackets for a shelf or the like, substantially as shown and described.

DESCRIPTION

FIG. 1 is a perspective view of a pair of support brackets for a shelf or the like showing my new invention.

FIG. 2 is a side, elevational view of the near bracket shown in FIG. 1, the corresponding side, elevational view of the bar bracket shown in FIG. 1 being a mirror-image of the view shown in FIG. 2.

FIG. 3 is bottom plan view of the near bracket shown in FIG. 1, the corresponding bottom plan view of the far bracket shown in FIG. 1 being a mirror-image of the view shown in FIG. 3.

FIG. 4 is a front, elevational view of the near bracket shown in FIG. 1, the corresponding front, elevational view of the far bracket shown in FIG. 1 being a mirror-image of the view shown in FIG. 4.

FIG. 5 is a rear, elevational view of the near bracket shown in FIG. 1, the corresponding rear, elevational view of the far bracket shown in FIG. 1 being a mirror-image of the view shown in FIG. 5.
